UNITED STATES PATENT OFFICE.

WILLIAM X. STEVENS, OF WASHINGTON, DISTRICT OF COLUMBIA.

AUTOMATIC SWITCH.

SPECIFICATION forming part of Letters Patent No. 400,802, dated April 2, 1889.

Application filed November 17, 1888. Serial No. 291,100. (No model.)

To all whom it may concern:

Be it known that I, WILLIAM X. STEVENS, a citizen of the United States, residing at Washington, in the District of Columbia, have 5 invented certain new and useful Improvements in Automatic Switches; and I do hereby declare the following to be a full, clear, and exact description of the invention, such as will enable others skilled in the art to which

10 it appertains to make and use the same.

This invention relates to that class of railroad-switches which have a pivoted tongue whose point may be swung from side to side to guide the flange of a car-wheel to run to 15 one side of the tongue or to the other side, according as the car is intended to follow the straight-line track or to turn off from it; and the object of the invention is to provide means whereby a switch-tongue may be automatically 20 turned to the right or left at the will of the car-driver without slackening speed, in darkness or light, or even if the switch be entirely under water, as frequently occurs in heavy rains.

25 To this end my invention consists in the construction and combination of parts forming an automatic switch, part of which is located upon the road and part of which is carried upon the cars, as hereinafter described 30 and claimed, reference being had to the accompanying drawings, in which—

Figure I represents a street-railway frog, showing the main characteristic of my invention. Fig. II represents a common style of 35 street-railway frog for the sake of comparison. Fig. III represents, in side elevation, one form of that portion of my switch which is carried upon the cars, including, also, a railway-frog and a portion of a car in longitudinal vertical 40 section. Fig. IV is a plan view of the drag. Fig. V is a plan view of the treadle with its box in horizontal section. Fig. VI is a vertical cross-section of my switch-frog at x x , Fig. I. Fig. VII is a plan view of a portion of a frog, 45 showing a modification of my invention. Fig. VIII is a longitudinal vertical section of the same on the line z . Fig. IX shows a double switch for turning the cars either to the right or left or allowing them to go straight ahead. 50 Fig. X is a rear view of the treadle-box, showing the upper treadle-arm in cross-section.

Fig. XI is an under side view of the point of a tongue on a larger scale.

6 represents the body of the frog, and 7 the tongue of the switch, pivoted at 8 to the 55 frog, so that its point may swing from side to side across the path of the car-wheel flange, as usual. This pivoted tongue is usually called the "switch;" but for sake of designation it will herein be called the "tongue." 60

10 represents a notch cut into the rail 9, or into that portion of a frog corresponding to the rail, and 25 represents a similar notch cut into the inside guard, 24, of the frog.

11 represents a wedge to be carried upon 65 each car to be dragged through the frog ahead of the car-wheel, and, by springing into the notch at that side of the tongue to which the car is to run, to wedge the tongue over into position to switch the car to that side. One 70 of the many methods in which this wedge may be carried upon the car is shown in Fig. III, in which 11 represents the wedge provided with a wheel, 12, projecting to one side of it to roll upon the track to carry the wedge at 75 the height to engage the tongue and broad enough in its tread to remain on the track while the wedge travels an inch or more inside of the track, as at 21.

13 is a treadle, pivoted at 14 in a box, 15, 80 which is secured to the front platform of the car directly over the inside edge of the rail.

16 is the lower arm of the treadle, to which the wedge 11 is attached by means of a drag-bar, 17. The parts 11, 12, and 17, taken collectively, are called the "drag." 85

18 is a spring attached to the arm 16 and to some fixed portion of the car, and it acts constantly to lift the drag up out of danger when not in service, and also to lift the treadle 90 up out of the way of passengers who may occupy the platform. Both arms of the treadle fit a vertical slot in the box 15, so guiding the treadle that when pressed down it carries the wedge directly down to the inner edge of the 95 rail. Were it not for this guiding-box the wedge would sometimes land on top of the rail and it might fail to work. The arm 16 also serves as a vertical journal on which the drag and the treadle may revolve a little from 100 side to side; but the groove in the box, before described, prevents this motion until the

treadle is pressed down below the sides of the groove, where it may pass either way under the knobs 19. If then set free, it will be raised behind the knob by the spring 18. 5 Thus the wedge will be held pressed either to the right or left as the treadle is behind the right or left knob. There is sufficient elasticity in the drag-bar 17 to compensate for the rocking of the car and to maintain the 10 wheel 12 upon the track when the drag is applied.

Let us suppose the car to travel in the direction indicated by the arrow 20 in Fig. I. Now, if the treadle be pressed down and 15 turned to the right, the wedge 11 will be pressed against the rail and the bar 17 will still be under tension to spring it farther to the right, so that when the wedge arrives at the switch it will be sprung into the right- 20 hand notch, 10, and, passing beside the point of the tongue, it will act between the wall of the notch and the tongue to wedge the tongue to the left out of its path, thus turning the switch to guide the car to the right; but if 25 the treadle be set to the left the wedge will be carried an inch or so from the rail, as shown at 21, until it strikes the flaring mouth 22 of the frog, when the drag-bar will yield as a spring until the left-hand notch, 25, is reached, 30 when the wedge will be sprung by the drag-bar into that, and if the tongue be at that side it will be thrown to the right. The sides of the tongue-point and the walls of the notches are slanted under, as shown in Fig. VI, and 35 the sides of the wedge 11 are slanted in the opposite direction, in order, first, that the wedge may hang to its work and not be forced upward out of engagement with the tongue and notch, even though the tongue be stuck 40 fast, and, second, in order that the action of the wedge may be to wedge the end of the tongue upward, so as to burst it loose from its bed on the frog, whether it be frozen or otherwise stuck down, and in order that it 45 may throw the tongue across while it is lifted free to avoid friction. The knobs 19 are not positively necessary to this invention, because the driver might hold the treadle pressed down and to either side with his foot; but the 50 knobs are beneficial in holding the drag as set, so that the driver may be at liberty after setting it to look to his car or horse.

On common street-car tracks a notch three-quarters of an inch into the side of the rail or frog beside the tongue is enough to admit the wedge, so that there is a portion of the track still left beside the notch for the wheel to travel on, thus avoiding any jolt in passing over the notch. Switch-tongues provided 55 each with a spring generally attached to the pivot beneath the frog to bear the tongue constantly to one side of the frog to favor the principal travel are common, and in connection with a tongue so provided it would be 60 only necessary to provide drags for those cars which must turn at the switch. In some cases, where the switch is seldom used, the wedge

may be carried upon the car to drag into this notch by the driver's hand, and in such a case the common poker would answer the purpose of a drag. As now used the poker has to be reached forward and deftly thrust down between the tongue and rail at an open point, 70 23, and then given a twist by hand to move the tongue. My notches 10 and 25 would enable the poker to be used as a drag or wedge carried upon the car. 75

In some cases my invention would work to good advantage by dragging a wedge upon the top of the rail near its inner edge to slide 80 down into the notch, as in the modification shown in Figs. VII and VIII. In both cases the principle of operation would be the same—a notch in the rail or frog beside the switch-tongue, and a wedge carried upon the car to 85 drag into the said notch. It might be possible for a wheel with a wedge-shaped edge traveling upon the rail-like wheel 12, in line of the notch 10, or of the parting between the point of the tongue and rail, to press down between the tongue and rail or frog, if the tongue had its corner beveled, so as to admit the entering wedge; but this would cause so much friction by downward pressure on the tongue that it would not be reliable. 90

Fig. IX shows a double switch in which two tongues are provided with springs, here concealed, to press them to each side, so as to leave the central line normally open. A car approaching this switch may set my drag to 100 turn it either upon the right or left hand track, or by leaving the drag out of service the car will continue straight ahead. Should the tongue spring back before the passage of the hind wheel of the car, a second drag may 105 be placed in front of the hind wheel and be connected with the front drag.

It is evident that any car may be provided with one right-hand drag and one left-hand drag to take the place of a single drag, hereinafore described, made adjustable for both 110 right and left movement.

The principal characteristic of this invention is the notch in the rail or frog. The wedge 11 might be a wheel or roller mounted 115 on a downward-projecting journal of the drag to roll against the side of the rail, the wall of the notch 10 being shaped as a wedge inclined toward the tongue, as shown.

In altering old frogs now in service it is a 120 simple matter to counterbore the two opposing notches at once and round the end corners a little with a cold-chisel.

The frog shown in Fig. II is common, having shoulders 27 to shield the front end of the 125 tongue and to prevent the flange of the wheel from wedging behind the tongue after it is set; but this shoulder, forming a notch in the rail at the end of the tongue, should not be mistaken for my notches beside the tongue, 130 which notches are always open whichever way the tongue sets.

In casting new frogs for my switches I would cut away the pattern not only to cast the

notches 10 and 25, but I would also leave out all that portion ahead of the notch 25 and within the dotted line 26, thus opening the mouth of the frog directly into the notch 25.

5 A flat piece of iron to drag upon the track in place of the wheel or roller 12 would answer the same purpose for a time, but would not operate as easily nor last as long.

I think that old frogs now in service could 10 be altered to conform to my invention at a cost of fifty cents each for the machine-work, and it is evident that after slightly altering the patterns new frogs may be made cheaper than the old by the weight of iron left out at 15 the notches, and that each car may be fitted with my device at a net cost of one dollar. I think this amount would be saved to every car company every year in the one item of damage to horses, because when a car runs past 20 its switch the driver must wait for help to back it, and the horse frequently gets tangled in the traces, kicks, and becomes balky. Besides this, the great convenience to the driver saves time on every trip, and the wedge dragging 25 through the frog tends to keep it cleaned from dirt and snow. The power of this wedge, backed by the momentum of the car, is enough to burst loose a tongue frozen down or to crush a common stone in the frog.

30 Having thus fully described my invention, what I believe to be new, and desire to secure by Letters Patent, is the following:

1. The combination of a railway-frog and a switch-tongue pivoted therein and having a 35 portion of its side edges slanted under, the edge of the rail portion of the frog also being slanted under beside the tongue, the said two slanting sides forming an aperture which in cross-section is wedge-shaped, with the base 40 of the wedge downward, and which in horizontal section is wedge-shaped, with the base of the wedge toward the point of the said tongue, substantially as shown and described.

2. A railway-switch tongue having a portion of its side edges slanted under near its 45 point, substantially as shown and described, whereby the under side of the point of the tongue is made a more obtuse wedge than the body of the tongue is.

3. The combination of the wedge 11, the 5° wheel 12, journaled thereto, and the drag-bar 17, adapted to be hung to a car, substantially as shown and described.

4. The combination of a switch-operating wedge, a wheel journaled thereon to roll on the track, and an elastic connection between the wedge and the car, substantially as shown and described, whereby the rocking of the car is compensated for and the wheel is maintained upon the track. 60

5. The combination of a switch-operating wedge hung upon a car and adapted to travel beside the rail, a device, substantially as described, upon the car for turning the wedge to the right and left, and a laterally-elastic 65 connection between the said device and wedge, whereby the wedge is elastically pressed to the side of the rail, as set forth.

6. The combination of a rail or frog having a notch in its side adapted to admit an operating-wedge, a switch-tongue located beside the said notch and pivoted to swing, a wedge carried upon a car, and a spring-connection between the wedge and the car, whereby the wedge is pressed upon the rail in a direction 75 to engage the said notch, substantially as shown and described. 70

In testimony whereof I affix my signature in presence of two witnesses.

WILLIAM X. STEVENS.
